UNITED STATES PATENT OFFICE.

ADOLPH WISSLER, OF ST. LOUIS, MISSOURI.

AIR-GUN.

1,073,454.

Specification of Letters Patent. Patented Sept. 16, 1913.

Application filed August 14, 1911. Serial No. 644,274.

To all whom it may concern:

Be it known that I, ADOLPH WISSLER, a citizen of the United States, residing at the city of St. Louis, State of Missouri, have invented a certain new and useful Improvement in Air-Guns, of which the following is a full, clear, and exact description, such as will enable others skilled in the art to which it appertains to make and use the same, reference being had to the accompanying drawings, forming part of this specification, in which—

Figure 1 is a sectional view through my improved air gun; Fig. 1^a is a top plan view 15 of the rear portion of the barrel; Fig. 1^b is a rear elevational view of the same; Fig. 2 is an enlarged view showing the valve and spring for supporting the same, and Fig. 3 is a plan view of the supporting spring.

20 This invention relates to a new and useful improvement in air guns, the object being to simplify the construction and reduce the cost of manufacture.

Another object is to make an air gun of 25 the take-down type.

With these objects in view, the invention consists in the construction, arrangement and combination of the several parts which will be hereinafter described and pointed out 30 in the appended claims.

My present invention is designed particularly as an improvement upon the air gun shown in the Benjamin Patent No. 822,645, dated June 5, 1906, to which reference may 35 be made for a fuller description of parts hereinafter shown but not described in detail.

In the drawings, 1 indicates the stock and 2 the piston barrel of the gun. The breech of this piston barrel is reinforced by a saddle plate 3 which may be soldered or otherwise secured in position thereon and which saddle plate serves for the attachment of a clamping bolt 4. The forward end of this barrel 2 is closed by a plug 5 serving as a 40 guide for the piston rod 6. An aperture 2^a is formed through the forward portion of the barrel 2, to permit the ingress of air to be compressed. The outer end of the piston 6 is provided with a button head 7. The inner end of piston 6 is slightly reduced to provide a shoulder against which a washer 8 is supported, said washer forming a backing for a rubber or 45 leather valve 9 held in position by means of the nut 10 threaded on the inner end of piston rod 6. 55 11 indicates a buffer spring surrounding the inner end of the piston rod so as to absorb shocks or jars incident to the outward pull of the piston rod. 60 In operation the piston is intended to be reciprocated so as to compress the air behind the same and force the compressed air through a tube 12 mounted in a partition wall 13 which wall forms the forward end of 65 the compression chamber. The tube 12 is flexible to some degree and carries at its inner end a valve support 14 provided with a stepped seat as shown in Fig. 2. This valve support is provided with a headed projection 15 on its under surface which co-operates with the narrow portion of a key-hole opening in spring 16. This spring is bent upon itself, the lower leg thereof resting 70 upon the bottom of barrel 2. 75 17 indicates a bent portion extending into the larger portion of the key-hole opening so that if it is desired at any time to remove the spring for the purpose of renewing the barrel, said spring may be pulled rearwardly and the tongue 17 will prevent the button-head 15 from engaging the spring and hence said spring may be readily removed. When removed, the valve support may be depressed and the valve 18 removed 80 for purposes of renewal. The valve 18 is in the form of a solid ball which rests upon the stepped valve seat and also closes an opening in a ported block 19, soldered or otherwise secured to the upper portion of 85 the barrel 2. This valve is intended to close the opening in the ported block, and, in operation, when air is compressed in the compression chamber by the reciprocations of the piston the said air will pass through the 90 tube 12 and pass between the stepped valve seat and the valve into the compression chamber, the spring 16 permitting the stepped valve seat to be moved downwardly 95 slightly for the passage of the incoming air. When the compression chamber is fully charged, which may require three or four strokes of the piston, depending upon the amount of pressure desired, the pellet indicated in dotted lines in Fig. 1, which is to 100 be shot from the gun, is dropped into muz- 105

zle of the barrel 20 when the gun is held upright until it reaches the contracted portion of said barrel as shown, where it is lodged by being wedged in place. This pellet is preferably globular in form and made of lead. The barrel 20 carries a front sight 21 and a rear sight 22. The rear end of the barrel 20 is closed, and a lateral port in its bottom communicates with the port in block 19. Preferably the side walls of barrel 20 are extended beyond the plug at its rear end so as to form a housing to protect the trigger 23 and serve as a guard to prevent the trigger from being actuated by an accidental blow on top. This trigger is in form of a bell-crank lever and is pivoted at 23^a in the rearwardly extending side walls of the barrel 20. The forward extension of the trigger is notched as designated by 23^b to form a seat for the upper end of a valve operating rod 24. This rod is provided with a cup at its bottom in a manner similar to that shown in the Benjamin patent, aforesaid, but, in addition, I have introduced a new element in the form of a pointed projection 25 preferably extending in axial alinement with the rod 24, and which enters the rubber ball valve so as to prevent the same from turning. This is desirable from the fact that the ball valves are molded and frequently the mold cavities do not register exactly and in consequence, there is left a rough, circumferential line incident to the parting line of the molds, which line, if the ball is turned so as to cause said line to intercept the valve seat, will prevent the valve from seating properly. By means of the pointed projection entering the valve, as shown, the valve is held in its proper position at all times and the parting line referred to may be kept located between the valve seats.

The rear end of barrel 2 is closed by a rubber cup-shaped packing 26 held in position by a metal washer 27, said washer, in turn, being backed by a cylindrical headed plug 28 which is slotted vertically for the passage of the trigger 23. A pin or screw 29 holds this cylindrical plug in position. I consider this construction important, as it has been found, in practice, that the manner of forming the rear wall of the compression chamber shown in the Benjamin patent, aforesaid, is objectionable, the threaded plugs frequently being blown out when a heavy charge is compressed in the chamber. The trigger 23 extends down through an opening in the stock and is operated within a trigger-guard 1^a secured to the stock. The upper portion of the trigger 23 extends through a vertical slot formed in the rear portion of the barrel 2 to the rear of the compression chamber therein, and the horizontally disposed upper end of said trigger occupies a vertical slot in the rear end of

the pellet barrel 20 to the rear of the shoulder therein against which the pellet rests prior to discharge.

To take down the gun, it is only necessary to remove the knurled nut 4^a from the bolt 4 and separate the stock from the barrel, said bolt and the trigger being lifted up through their respective openings. To assemble the gun, of course the reverse operation is followed. The operation of charging, loading and firing the gun is perhaps obvious from the above. As stated before, the piston is reciprocated according to the desired amount of pressure required in the compression chamber. Preferably, the button-head of the piston is placed on the floor and held by the foot of the operator and the gun moved up and down. In this manner the operator can place his entire weight on the stock of the gun and not only secure a greater compression, but, by having the muzzle pointed downward, the danger of an accidental discharge, when the pellet is in the gun, is avoided.

It will be readily understood that minor changes in the size, form and construction of the various parts of my improved air rifle may be made and substituted for those herewith shown and described without departing from the spirit of my invention, the scope of which is set forth in the appended claims.

I claim:

1. In an air gun, a tube having a compression chamber at its rear end, a pellet tube attached to the first mentioned tube, which pellet tube is in communication with said compression chamber, the rear end of said pellet tube being slotted, a valve controlling the port of communication between the compression chamber and pellet tube, a valve pin projecting into the slot in the pellet tube, and a trigger having a portion positioned in the slot in the pellet tube and engaging said pin.

2. In an air gun, the combination with a compression chamber having an ingress valve opening, of a ball valve normally closing the ingress opening, a cup normally engaging said ball valve, a resilient tube leading into the compression chamber and carrying the cup, a headed projection on the underside of the cup, and a flat spring having one end detachably connected to said headed projection and the opposite bearing against the wall of the compression chamber.

3. In an air gun, the combination of a compression chamber, a yielding tube leading thereto and carrying a valve seat at its inner end, a valve cooperating with said seat, and a removable flat spring folded upon itself and arranged under said valve seat to force the same upwardly against said valve.

4. In an air gun, the combination of a compression chamber, a yielding valve seat arranged therein, a valve coöperating with said seat, and a flat spring coöperating with said valve seat; said spring having a key hole opening for engagement with the valve seat.
5. In an air gun, the combination of a compression chamber, a yielding valve seat arranged therein, a valve coöperating with said seat, a flat spring coöperating with said valve seat; said spring having a key hole opening for engagement with the valve seat, and a bent tongue extending into the larger portion of said key hole opening for assisting in the disengagement between said spring and said seat.
6. In an air gun, the combination of a compression chamber, a pellet barrel, a ported block leading into said pellet barrel, an egress valve for controlling the passage of air from said compression chamber to said pellet barrel, the rear end of said pellet barrel being slotted vertically, a valve operating rod arranged in said slot, and a trigger also pivotally mounted in said slot for co-operating with said rod.
7. In an air gun, the combination of a compression barrel and a pellet barrel, the rear end of said compression barrel having a compression chamber and both of said barrels being slotted vertically at their extreme rear ends, a trigger extending through the slots in said barrels, and a valve coöperating with said trigger for controlling the air from the compression chamber to said pellet barrel.
8. In an air gun, the combination of a compression barrel, a compression chamber arranged at the rear end of said barrel, a cup-shaped yielding washer forming the rear wall of said compression chamber, a disk-shaped washer for supporting the first mentioned washer in position, a plug for holding said last mentioned washer in place, and a pin for securing said plug in position.
9. In an air gun the combination with a tubular member provided with a compression chamber at its rear end, a hollow plug seated in the rear end of said tubular member and forming the rear head of the compression chamber, said plug and the rear end of the tubular member being slotted to receive the air gun trigger.
10. In an air gun, the combination of a compression chamber, a pellet barrel the rear end of which is slotted, a valve operating rod extending into the slotted rear end of said pellet barrel, and a trigger pivotally mounted so as to coöperate with said valve operating rod; a portion of which trigger occupies the slot in the rear end of said pellet barrel.
11. In an air gun the combination with a compression barrel, of a pellet barrel, the rear ends of which barrels are vertically slotted, a stock detachably applied to the compression barrel, and a trigger positioned in the slots of the compression and pellet barrels and extending through an opening in the stock.
12. In an air gun, the combination of a compression barrel having a compression chamber at its rear end, a pellet barrel secured thereto, a valve for controlling the egress of air from said compression chamber to said pellet barrel, the rear ends of said barrels being slotted vertically, a trigger pivotally mounted in said slot for operating said valve, a stock through which said trigger passes, and a bolt secured to the compression barrel and extending through an opening in said stock; said bolt being provided with a nut to separably secure said parts together.
- In testimony whereof I hereunto affix my signature in the presence of two witnesses, this 9th day of August, 1911.
